UNITED STATES PATENT OFFICE

114,578

DESIGN FOR A DECK OF PLAYING CARDS

Otis E. Keene, New York, N. Y.

Application February 17, 1939, Serial No. 83,046

Term of patent 14 years

To all whom it may concern:

Be it known that I, Otis E. Keene, a citizen of the United States and residing at New York, in the county of Bronx and State of New York, have invented a new, original, and ornamental Design for a Deck of Playing Cards, of which the following is a specification, reference being had to the

accompanying drawings, forming part thereof.

Figs. 1 to 8 are plan views of the deck of playing cards, showing my new design.

I claim:

The ornamental design for a deck of playing cards, substantially as shown.

OTIS E. KEENE.
